(57) **CLAIM**

The ornamental design for lamp packages, as shown and described.

DESCRIPTION

FIG. 1 is a top perspective view of the lamp package showing our design;

FIG. 2 is a bottom perspective view thereof;

FIG. 3 is a top view thereof;

FIG. 4 is a bottom view thereof;

FIG. 5 is a side view thereof thereof; and,

FIG. 6 is a opposing side view thereof.

FIG. 7 is a top perspective view of another embodiment of the lamp package showing our design;

FIG. 8 is a bottom perspective view thereof;

FIG. 9 is a top view thereof;

FIG. 10 is a bottom view thereof;

FIG. 11 is a side view thereof; and

FIG. 12 is an opposing side view thereof.

FIG. 13 is a top perspective view of another embodiment of the lamp package showing our design;

FIG. 14 is a bottom perspective view thereof;

FIG. 15 is a top view thereof;

FIG. 16 is a bottom view thereof;

FIG. 17 is a side view thereof; and

FIG. 18 is an opposing side view thereof.

FIG. 19 is a top perspective view of another embodiment of the lamp package showing our design;

FIG. 20 is a bottom perspective view thereof;

FIG. 21 is a top view thereof;

FIG. 22 is a bottom view thereof;

FIG. 23 is a side view thereof; and,

FIG. 24 is an opposing side view thereof.

The broken lines shown herein are for environmental purposes only and form no part of the claimed design. The illustrated device is not limited to the scale shown. As shown in FIGS. 1, 3, 7, 9, 13, 15, 19, 21, & 25, the upstanding medial projection is a lens portion of the lamp package that is optically transparent. As shown in FIGS. 3, 9, 15 & 21, the lens portion is optically transmissive such that the LED chip and associated unclaimed contact leads are visible through the transparent lens portion of the lamp package.
